UNITED STATES PATENT OFFICE

ALFRED A. GLIDDEN, OF WATERTOWN, AND WALTER R. HICKLER, OF WESTON, MASSACHUSETTS, ASSIGNORS TO HOOD RUBBER COMPANY, OF WATERTOWN, MASSACHUSETTS, A CORPORATION OF MASSACHUSETTS

WATERPROOF SHOE

Application filed November 6, 1928. Serial No. 317,559.

This invention relates to an improved overshoe or shoe, embodying therein a waterproof upper.

The object of the invention is to provide a shoe or overshoe embodying therein an upper preferably waterproof and vulcanizable, said upper being composed substantially of a single sheet of material which may represent woolen, felted and knitted fabrics, 10 or certain soft tanned leathers. When ground leather is used for the outer layer of the fabric forming the upper, a leather appearance is given to the upper. Pigments may be used in the said upper to obtain fine 15 decorative effects. When long hair is used on the outer surface of the upper, a fur effect may be obtained. Thus it will be seen that according to the material used on the outer face of the fabric, different appearing materials may be produced.

The object of the invention is, therefore, to provide a shoe or overshoe embodying therein a waterproof vulcanizable upper which, while presenting the appearance on 25 the outside of a fabric or of soft leather, shall have a stockinet or other desired inner face, while intermediate the inner and outer faces there are two layers of elastic gum compound.

While embodying these characteristics the invention embodies a shoe or overshoe, the different materials of which the upper is composed being so associated and intermingled as to form in function and in effect 35 a single-ply material.

Another object of the invention is to complete the upper before any part of it is placed on the last in the manufacture of the shoe as distinguished from the prior art in 40 overshoe manufacture, wherein the upper was constructed of a plurality of pieces of material and built up piece by piece on the last.

The upper of the shoe of this invention 45 consists of a sheet of material which has, in combination, an inner layer, preferably of fabric, an outer layer of particles of material, preferably fibrous material, such as flock, and an intermediate layer of elastic compound superimposed upon the inner layer.

of fabric, and another layer of elastic gum compound having incorporated therein a substantial quantity of flock, ground leather fiber, wood flour, or the like. To this last-named layer, said outer layer of particles of material is attached by a layer of adhesive material having small particles of material, 55 preferably fibrous material, therein.

The intermediate layer of elastic gum compound and the layer of adhesive material preferably have sulphur and other materials, such as an accelerator, preferably diphenylguanidine, incorporated therein, and also a metallic oxide, preferably zinc oxide. These materials incorporated in the 60 layer of elastic gum compound and the layer of adhesive material render these layers vulcanizable, thus the upper may be vulcanized prior to or after its incorporation in a 65 complete shoe.

The upper of the shoe of this invention is not only waterproof and vulcanizable, but is flexible to a high degree, because of the structure embodied therein and, therefore, 70 resists the wearing action or bending to a marked degree.

Prolonged life of the upper of the shoe of this invention is obtained as it is a well-known fact that articles made of rubber or rubber compound and articles made of rubber or rubber compound coated textile material deteriorate to a greater or less degree when exposed to the action of certain rays of light, such as may be found in sunlight.

In the upper of the shoe of this invention 85 the outside layer being composed of millions of small pieces, preferably of fibrous material, which are firmly fixed to and which completely cover the elastic gum compound layer referred to, protect it and the other 90 layer of elastic rubber compound from the penetration of light and from oxidation, thereby greatly prolonging the life of the shoe upper.

If desired, the fiberized surface of the upper 95 may be embossed to produce different effects. The underlying yielding structure of the layers of elastic rubber compound and elastic gum compound being readily formed 100 into any design desired. The fiberized sur-

face of the overshoe upper may be printed upon by employing the well-known process of textile print work, or it may be printed upon by impression, such, for instance, as would be produced by a rotary or platen press.

By depositing different colored fibers in different places on the gum compound surface, designs of many kinds will be readily obtained.

10 The invention consists in the improved shoe or overshoe set forth in the following specification and particularly pointed out in the claims.

15 Referring to the drawings:

Figure 1 is a side elevation of an overshoe embodying our invention.

Fig. 2 is a detail section of a portion of the upper as taken on the line 2—2 of Fig. 1 and 20 made upon a very much enlarged scale.

Like numerals refer to like parts throughout the several views of the drawings.

In the drawings, 4 is the sole and 5 is the upper of the overshoe of our invention. The 25 sheet material of which the upper is composed, see Fig. 2, consists of a layer of sheet material such as fabric 6, a layer 7 of elastic compound such, for example, as rubber compound, a layer 8 of elastic gum compound, a 30 layer 9 of adhesive material such as elastic gum cement, which is applied to the layer 8, and a layer 10 positioned on the layer 9 and consisting of small particles of material which may be fibrous material such as flock, 35 where it is desired to produce in the fabric the effect of a woolen, felted, or knitted fabric, or where it is desired to present an appearance of certain soft tanned leathers, ground leather may be used.

40 The layer 8 of elastic gum compound and the layer 9 of adhesive material also preferably have incorporated therein small particles of material, which may be fibrous material such as flock, where it is desired to produce in the fabric the effect of a woolen, felted, or 45 knitted fabric, or where it is desired to present an appearance of certain soft tanned leathers. Preferably, the small particles of material in the layers 8 and 9 will be the same as the particles of material incorporated in the layer 10, so that as the fabric wears in use the same appearance will be presented to the eye when the layer 10 is worn off, or partly worn off, due to the small particles of material in the 55 layer 9, and when the layer 9 is worn off, or partly worn off, the same appearance will be presented to the eye by the fabric on account of these small particles of material being incorporated in the layer 8.

60 According to the material which is used in the layers 8, 9, and 10 and the degree of fineness to which it is ground, different appearances may be given to the shoe upper and the color used for these different layers may be 65 varied according to the pigments which are

used in said layers, and where pigments are used, the same pigments would preferably be used in the layer of adhesive material 9 and in the layer 8, so that as the article is worn it will still keep the same color. For the layer 70 6 different materials may be used, such as woven fabric, knitted goods, stockinet, and the like, the use of such fabric depending upon the results which it is desired to attain. The layer 7 being made of an elastic compound such as rubber compound, without any particles of fabric in it, renders the fabric as a whole waterproof.

75 In manufacturing the sheet material of which the upper is composed the layer of fabric 6 may be of woven cloth or knitted fabric, or other textile fabric, and this is passed through a calender and the elastic compound layer 7 is applied to the fabric layer 6 and is driven by pressure in between the 80 yarns that make up the fabric on one face of the layer 6. This is the well-known coating process regularly carried on in rubber mills. The elastic gum compound layer 8 with the 85 fine particles of material hereinbefore set forth incorporated therein is applied to the elastic compound layer 7, and the layer 9 consisting of a light coat of elastic gum cement with the fine particles hereinbefore set forth incorporated therein, is applied to the elastic gum compound layer 8, the layer 9 constituting an adhesive. The elastic gum cement of the layer 9 having the particles of fibrous material, or other fine particles hereinbefore named, or other equivalents, incorporated therein, may be applied to the layer 8 by passing the layers 6, 7 and 8 over a roll and under a sharp straight edge; then while the elastic gum cement is still sticky and before the solvent therein has evaporated, the cement coated fabric will next pass underneath a device from which the material with which the layer 9 is to be faced is delivered, that is, the fine particles of flock etc., hereinbefore set forth. The surplus material not taken up and not firmly positioned upon the layer 9 is then removed by suction, leaving an even deposit of small pieces of material forming the layer 10, which may be flock or any fibrous material or other material according to the desired finish of the material of which the shoe upper is formed.

100 The machine described for the manufacture of the material of the shoe upper is to be made the subject-matter of a separate application for United States Letters Patent.

105 After the upper has been manufactured as hereinbefore described, the sole 4 is attached thereto in any well-known or suitable manner as by means of adhesive material and pressure.

110 It will be understood that this invention relates to an overshoe or a shoe and the sole 4 115 may be of rubber compound or of leather, 120

or of any other material which is practicable for the purpose.

While the article of footwear of this invention is set forth in the claims as an overshoe, it may also include shoes, as set forth in the specification, and also slippers or the like, without departing from the spirit of this invention, and in the specification and claims the word overshoe is to be read with 10 this understanding.

We claim:

1. An overshoe or the like embodying therein a waterproof upper comprising an inner layer of sheet material, a layer of elastic compound superimposed thereon, a layer of elastic gum compound containing a quantity of fibrous material applied to said layer of elastic compound, a layer of adhesive material containing small particles of fibrous material applied to said layer of elastic gum compound, and a layer of small particles of material superimposed upon said layer of adhesive material.

2. An overshoe or the like embodying 25 therein a waterproof upper comprising waterproof sheet material embodying therein a layer of fabric, a layer of rubber compound superimposed thereon, a layer of elastic gum compound containing a quantity 30 of fibrous material applied to said layer of rubber compound and projecting thereinto, a layer of adhesive material containing small particles of fibrous material applied to said layer of elastic gum compound, and 35 a layer of small particles of material attached to the layer of adhesive material.

3. An overshoe or the like embodying 40 therein a vulcanizable waterproof upper comprising an inner layer of sheet material, a layer of elastic compound superimposed 45 thereon, a layer of elastic gum compound containing a quantity of fibrous material applied to said layer of elastic compound, a layer of adhesive material containing small particles of fibrous material attached to said layer of elastic gum compound, and a layer 50 of small particles of material attached to said layer of adhesive material.

4. An overshoe or the like embodying 55 therein a vulcanizable waterproof upper embodying therein an inner layer of sheet material, a layer of elastic compound superimposed thereon, a layer of elastic gum compound containing a quantity of fibrous material applied to said layer of elastic compound, a layer of adhesive material containing small particles of fibrous material attached to said layer of elastic gum compound, and a layer of small particles of material 60 attached to said layer of adhesive material, said layers of elastic gum compound and adhesive material containing sulphur, a metallic oxide, and an accelerator, whereby the upper is rendered vulcanizable.

65 5. An overshoe or the like embodying

therein a vulcanizable waterproof upper embodying therein an inner layer of sheet material, a layer of elastic compound superimposed thereon, a layer of elastic gum compound containing a quantity of fibrous material applied to said layer of elastic compound, a layer of adhesive material containing small particles of fibrous material attached to said layer of elastic gum compound, and a layer of small particles of material attached to said layer of adhesive material, said layers of elastic gum compound and adhesive material containing sulphur, zinc oxide and diphenylguanidine, whereby the upper is rendered vulcanizable.

In testimony whereof we have hereunto set our hands.

ALFRED A. GLIDDEN.
WALTER R. HICKLER.
